INVENTOR.

John S. Wilson

UNITED STATES PATENT OFFICE.

JOHN S. WILSON, OF INDIANAPOLIS, INDIANA.

ADJUSTABLE TABLE.

SPECIFICATION forming part of Letters Patent No. 274,162, dated March 20, 1883.

Application filed November 13, 1882. (No model.)

To all whom it may concern:

Be it known that I, JOHN S. WILSON, of Indianapolis, Indiana, have invented a new and useful Improvement in Adjustable Tables, of which the following is a description, reference being made to the accompanying drawings, in which like letters indicate like parts.

My invention consists in a flat top which revolves upon journals having bearings in side supports, and in connecting-braces which are adjustable, and which will support the top in either a horizontal or vertical plane, or at any angle between such planes, and means for securing the same in any desired position.

My object is to furnish a device which may indifferently be used for a work-table, game-table, blackboard, drafting-board, easel, and for other purposes of the kind, and which will be economical in cost and simple in construction.

In the drawings, Figure 1 is a perspective view of my device, showing the top T adjusted at an angle from the vertical, and the dotted lines show the position of the top and side brace, B, when the top is horizontal and ready for use as a table. Fig. 2 is a vertical section through one of the side supports and braces, showing the top T in a perpendicular position.

In these figures, S. S are upright supports on each side, slotted in the central portions of their lengths and connected by ordinary stretchers. B is a brace slotted longitudinally and pivoted at P to the top T. J J are the journals or gudgeons, set in or secured to the sides of the top T, and having bearings in the supports S. S. A thumb-screw for holding the brace in any desired position is shown at t.

My device operates as follows: If it is desired to form a flat top for use as a table of any kind, supposing the position of the part T to be that shown in Fig. 1, the thumb-screw t is loosened and the piece T pushed over from the operator, and it will then occupy the position shown in the dotted lines above, the brace taking the position shown in the oblique dotted lines. It will then be in a proper position, and by tightening the thumb-screw will be held firmly. If desired, a slotted brace may be attached to the other side of the table to make it more firm; but if two such braces are used they must be pivoted at opposite

ends of the top T; or, again, supposing the device to occupy a position in which the top T stands vertically between the side supports, and has been used, one side of it as a blackboard, if, now, it is desired to use it as a table, in an emergency, it may be revolved completely, so as to bring the other side up level as a table, and it may be used as such without marring or rubbing out the work on the blackboard. The device may be operated by any one after a little practice; but it must be borne in mind that the end of the brace B, which is pivoted to the top T, must always pass over the end of the post or support S. For this purpose the pivoted end of the brace B has a shoulder formed on it, as shown in Fig. 2.

By attaching a strip to either end of the top T to form a support, my device may be used as a sort of easel to support pictures or engravings.

What I claim, and desire to secure by Letters Patent, is—

1. As an article of manufacture, a portable table whose top revolves between two standards or side posts upon journals having bearings therein, one or both of which side posts are slotted longitudinally, and having an adjustable brace slotted longitudinally, pivoted to the top, and united at its other end to one of the side posts by a thumb-screw or its equivalent, whereby the top may be secured in any desired position or angle, substantially as and for the purpose described.

2. A table whose top is supported on bearings in two side supports, and adapted to revolve thereon, and having one or more slotted side braces which are connected with one or more of the side supports, which are slotted to allow the bolt of a thumb-screw connecting the brace and post to move up and down therein for securing the top in any position, substantially as and for the purpose described.

3. The combination of the top T, revolving between the posts S S, one or both of which are slotted longitudinally, the slotted brace B, pivoted to the top, and means for holding the brace at any angle and securing it to the side post, substantially as and for the purpose described.

4. The frame-work of a table, having two

side posts, one or both of them slotted longitudinally, supporting a top which revolves in bearings on such side posts and between them, in combination with one or more lateral braces for sustaining such top at any desired angle, connected with the side posts, substantially as described.

In witness whereof I have hereunto set my hand this 10th day of November, 1882.

JOHN S. WILSON.
